UNITED STATES PATENT OFFICE

172,854

DISH COVER

James C. Waldo, Toledo, Ohio

Application April 7, 1953, Serial No. 24,384

Term of patent 14 years

(Cl. D44—15)

To all whom it may concern:

Be it known that I, James C. Waldo, a citizen of the United States of America, residing at Toledo, Lucas County, Ohio, have invented a new, original, and ornamental Design for a Dish Cover, of which the following is a specification, reference being had to the accompanying drawing, forming a part hereof.

Fig. 1 is a side elevation view of a dish cover, showing my new design;

Fig. 2 is a top plan view thereof, and

Fig. 3 is a fragmentary sectional view in vertical section of the stepped rim portion at the right of Fig. 1.

This is a continuation-in-part of application

Serial No. D. 17,475, filed November 20, 1951, and which is now abandoned.

I claim:

The ornamental design for a dish cover, as shown.
